(57) **CLAIM**

We claim the ornamental design for an electrical connector,
as shown and described.

DESCRIPTION

FIG. 1 is a top, front perspective view of an electrical connector according to a first embodiment of our new design;

FIG. 2 is a top view of the electrical connector according to the first embodiment;

FIG. 3 is a bottom view of the electrical connector according to the first embodiment;

FIG. 4 is a left side view of the electrical connector according to the first embodiment;

FIG. 5 is a right side view of the electrical connector according to the first embodiment;

FIG. 6 is a front view of the electrical connector according to the first embodiment;

FIG. 7 is a rear view of the electrical connector according to the first embodiment;

FIG. 8 is a cross-sectional view of the electrical connector taken along line 8-8 in FIG. 6 according to the first embodiment;

FIG. 9 is a cross-sectional view of the electrical connector taken along line 9-9 in FIG. 2 according to the first embodiment;

FIG. 10 is a top, front perspective view of an electrical connector according to a second embodiment of our new design;

FIG. 11 is a top view of the electrical connector according to the second embodiment;

FIG. 12 is a bottom view of the electrical connector according to the second embodiment;

FIG. 13 is a left side view of the electrical connector according to the second embodiment;

FIG. 14 is a right side view of the electrical connector according to the second embodiment;

FIG. 15 is a front view of the electrical connector according to the second embodiment;

FIG. 16 is a rear view of the electrical connector according to the second embodiment;

FIG. 17 is a cross-sectional view of the electrical connector taken along line 17-17 in FIG. 15 according to the second embodiment;

FIG. 18 is a cross-sectional view of the electrical connector taken along line 18-18 in FIG. 11 according to the second embodiment;

FIG. 19 is a top, front perspective view of an electrical connector according to a third embodiment of our new design;

(Continued)

FIG. 20 is a top view of the electrical connector according to the third embodiment;
FIG. 21 is a bottom view of the electrical connector according to the third embodiment;
FIG. 22 is a left side view of the electrical connector according to the third embodiment;
FIG. 23 is a right side view of the electrical connector according to the third embodiment;
FIG. 24 is a front view of the electrical connector according to the third embodiment;
FIG. 25 is a rear view of the electrical connector according to the third embodiment;
FIG. 26 is a cross-sectional view of the electrical connector taken along line 26-26 in FIG. 24 according to the third embodiment;
FIG. 27 is a cross-sectional view of the electrical connector taken along line 27-27 in FIG. 20 according to the third embodiment;
FIG. 28 is a top, front perspective view of an electrical connector according to a fourth embodiment of our new design;
FIG. 29 is a top view of the electrical connector according to the fourth embodiment;
FIG. 30 is a bottom view of the electrical connector according to the fourth embodiment;
FIG. 31 is a left side view of the electrical connector according to the fourth embodiment;
FIG. 32 is a right side view of the electrical connector according to the fourth embodiment;
FIG. 33 is a front view of the electrical connector according to the fourth embodiment;
FIG. 34 is a rear view of the electrical connector according to the fourth embodiment;

FIG. 35 is a cross-sectional view of the electrical connector taken along line 35-35 in FIG. 33 according to the fourth embodiment; and,
FIG. 36 is a cross-sectional view of the electrical connector taken along line 36-36 in FIG. 29 according to the fourth embodiment.
The broken lines shown in the drawings are included for the purpose of illustrating portions of the electrical connector that form no part of the claimed design.

1 Claim, 12 Drawing Sheets
